UNITED STATES PATENT OFFICE.

JOHN F. STREIB, OF LOS ANGELES, CALIFORNIA, AND MINOT C. BLEST, OF BELLEVUE, PENNSYLVANIA, ASSIGNEES TO PRESSED STEEL CAR COMPANY, OF PITTSBURGH, PENNSYLVANIA, A CORPORATION OF NEW JERSEY.

MINE CAR.

Application filed May 25, 1922. Serial No. 563,670.

Referring to the drawings in which like reference characters refer to like parts, Fig. 1 is a plan view of a mine car embodying the invention; Fig. 2 is a side elevational view of the same; Fig. 3 is an enlarged end elevational view of the same; Fig. 4 is an enlarged cross sectional view of the same taken on the line 4—4 of Fig. 1, and Fig. 5 is an enlarged longitudinal sectional view taken on the line 5—5 of Fig. 1.

Referring now in detail to the drawings, the reference character 1 indicates the floor of the car, 2 the side walls and 3 the end walls.

15 The floor 1 comprises a horizontally disposed plate 4 which preferably extends in one piece from side to side and from end to end of the car. At the sides and ends of the car, angles 5 and 5^a respectively are provided, one flange of each of which is disposed horizontally and is secured to the floor plate 4 while the other flange is disposed vertically upward. Beneath the floor plate 4 and on each side of the transverse center line of the car, a transverse member 6 is provided which preferably extends for the full width of the car. Each of these members is preferably of Z shape in cross section, having a vertically disposed web 7 and top and bottom horizontally disposed flanges 8 and 9 respectively. The top flange 8 extends inwardly in a direction toward the transverse center line of the car and contact with the underside of the floor plate 4, and is secured 30 to such plate and to the horizontally disposed flanges of the angles 5. The bottom flange 9 extends outwardly in a direction toward the end of the car and is spaced away from the floor plate 4 and forms a support for the rear end of a buffer block 10. At each end of the car and beneath the floor thereof spaced longitudinal members 11 are provided which preferably extend outwardly from the member 6 to the end of the car. 45 Each of these members is preferably Z shaped in cross section having a vertically disposed web 12, a horizontally disposed outwardly extending top flange 13 which is secured to the floor plate 4, and a horizontally disposed inwardly extending bottom flange 14 which serves as an additional support for the buffer block 10. The buffer blocks 10

are preferably made of wood and each is secured to the floor of the car, transverse member 6 and angle 5^a by vertical bolts, and to the webs 12 of the longitudinal members 11 at one end of the car by transverse bolts. The outer end portion of the block extends beyond the end of the car and is provided with a metallic buffer plate 15.

Intermediate the transverse members 6 and adjacent each side of the car the floor plate 4 is provided with an opening which preferably extends from the member 6 at one end of the car to the member 6 at the opposite end of the car. Each of these openings is covered by a member 16 having an upwardly extending hood portion 17 having closed ends and horizontally disposed end and side flanges 18 and 19 respectively which are preferably integral with the hood portion 17 and with each other. The end flanges 18 are secured to the top flanges 8 of the transverse members 6 and the side flanges 19 are secured to the floor plate 4. Each of these members 16 when secured in this manner form a recess 20 for the reception of the upper portions of the wheels 21, at each side of the car, which are mounted on axles 22 suitably journaled in boxes 23 which are secured to the floor plate 4, angle 5 and one of the flanges 19. Between the members 16 and at substantially the longitudinal center line of the car a longitudinal member 24 is provided which preferably extends from the angle 5^a at one end of the car to the angle 5^a at the opposite end. This member has horizontally disposed side and end portions 25 and 26 respectively which rest on the upper surface of the floor plate 4 and are secured to such plate and to the transverse members 6 and buffer blocks 10. Intermediate the side portions 25 this member is provided with an upwardly disposed corrugation 27 which preferably terminates short of the ends of the member. It will here be noted that the angles 5, transverse members 6, hooded members 16 and member 24 when secured together as just described, form a strong frame-work for the floor which is well adapted to carry the weight of the loading as well as withstand heavy buffing and pulling shocks to which a mine car is subjected.

Beneath the floor of the car a brake mechanism is provided which comprises transverse brake beams 28 having brake heads 29 secured to the end portions thereof which are operated by a plurality of connected rods and levers. To support these brake beams, members 30 are provided, the lower end of each of which is pivotally connected with one of the brake heads 29 at one end of one of the beams, the opposite end being hook shaped and adapted to engage a support 31 which is secured to the hooded portion 17 of the member 16 and within the recess 20 formed by such portion, thus permitting the brake to be applied close to the underside of the floor 4 and at the same time provide the proper hanging for such brake.

Each of the end walls 3 of the car comprises a vertically disposed plate 32, the lower portion of which is secured to the vertical flange of the angle 5. Each of the side walls 2 comprises a vertically disposed plate 33 the lower portion of which is secured to the vertical flange of the angle 5. The adjacent vertical edge portions of these side and end walls are preferably connected together through the medium of vertically disposed angles 34, each of which is secured to one of the end walls and to one of the side walls by rivets or other suitable means. To strengthen the end wall, a coping iron 35 is provided which extends from side to side of the car and is secured at intervals throughout its length to the upper edge portion of the plate 32. To strengthen the side wall a coping iron 36 is provided which extends from end to end of the car. This member is provided with an upstanding inner flange 37 which is secured at intervals throughout its length to the upper portion of the side plate 33, a horizontally disposed web 38 and a downwardly and inwardly directed outer flange 39. The web 38 adjacent the ends of the car is gradually reduced in depth as indicated by the reference character 40 so that at the end of the car there is only the thickness of the metal from which the member is made projecting outwardly from the side wall. It will here be noted that by turning the flange 39 slightly inward and tapering the web 38, sharp edges and corners are eliminated, thus obviating accidents caused by sharp edges or corners cutting workmen working near the car or catching in their clothing.

At the ends of the car coupling devices 40^a are provided, each of which comprises a hollow casing member 41 arranged within the body of the car and secured to one of the end portions 26 of the member 24 and to the adjacent end wall 3. Mounted in the casing and movable longitudinally relative thereto, is a draw bar 43 which at its inner end within the casing 41 is preferably provided with a spring seat 44. The outer end

of this draw bar extends beyond the end wall and is provided with a coupling pin 45 which when the car is being dumped by the use of a rotary dumping machine and rotated in the direction of the arrow in Fig. 3, 70 is prevented from dropping out of the draw bar by a dog 46 which is pivotally mounted on the end wall 2 above the pin 45, excessive movement of such dog being prevented by a bolt 47 or any other suitable means. To 75 cushion the pulling shocks to which a car of this type is subjected, a spring 48 is provided one end of which is seated against one of the end walls of the casing member 41 and the opposite end against the spring seat 80 44 secured to the draw bar.

It will be apparent to those skilled in the art to which this invention appertains that many changes may be made in the details of the several parts forming the invention 85 without departing from the spirit and scope of the appended claims.

Having thus described the invention what we claim as new and desire to secure by Letters Patent is:—

1. In a mine car, a floor, transversely extending members arranged beneath and secured to said floor and longitudinally extending members arranged above and secured to said floor and transverse members, said longitudinal members being adapted to receive portions of the wheels of said car, and a corrugated member arranged between the last mentioned members and secured to said floor and transverse members. 95

2. In a mine car, a floor having an opening formed therein adjacent each side of the car, wheels extending through said opening, a hooded member secured to said floor adapted to cover the portions of said wheels which extend through said floor, a brake mechanism arranged beneath said floor and hangers for said brake mounted in said members. 105

3. In a mine car, a floor, wheels having portions extending through said floor, a member secured to said floor covering said wheel portions, a brake mechanism for said car, and hangers for said brake mounted in said member. 110

4. In a mine car, a floor, wheels mounted on said car having portions extending above the top of said floor, members secured to said floor and adapted to form recesses for said wheels, and a brake mechanism and brake hangers mounted in said members. 120

5. In a mine car, a side wall, a coping member secured to said wall, said member having a horizontally disposed web reduced in depth toward its ends and a downwardly and inwardly extending flange continuous for the full length of said web. 125

6. In a mine car, a side wall and a longitudinal strengthening member secured to said side wall, said member being of Z- 130

shape for substantially its full length and reduced in depth at its ends.

7. In a mine car, a side wall, and a longitudinal strengthening member having an up-

wardly extending flange secured to said wall, a horizontal web the end portions of which are gradually reduced in depth, and a down-

wardly extending flange continuous for substantially the full length of said member.

In testimony whereof we affix our signatures.

JOHN F. STREIB.
MINOT C. BLEST.
